F. KUCAB.
COMBINATION COMB AND BRUSH,
APPLICATION FILED JULY 17, 1920.

1,356,637.

Patented Oct. 26, 1920.

Inventor
F. Kucab
By his Attorney
Marie Salter

UNITED STATES PATENT OFFICE.

FRANCISZEK KUCAB, OF DAYTON, OHIO.

COMBINATION COMB AND BRUSH.

1,356,637.

Specification of Letters Patent.

Patented Oct. 26, 1920.

Application filed July 17, 1920. Serial No. 397,095.

To all whom it may concern:

Be it known that I, FRANCISZEK KUCAB, a citizen of Poland, residing at Dayton, in the county of Montgomery and State of 5 Ohio, have invented certain new and useful Improvements in Combination Combs and Brushes, of which the following is a specification.

The main object of this invention is the 10 provision of a combined comb and brush in a single unit, the comb being readily brought into position for use or concealed, as desired.

Another object of the invention is the 15 provision of a novel, quick and reliable-acting mechanism for thus moving said comb into position for use or into concealed position.

The above and other objects of the invention 20 will become apparent in the description below, in which characters of reference refer to like-named parts in the drawings.

Referring briefly to the drawings, Figure 1 is a view of the underside of my device, 25 part of the frame thereof being removed.

Fig. 2 is a side elevational view of the same, partly in section.

Fig. 3 is a view of the underside of the 30 same, part of the frame thereof being removed, the comb being shown in another position.

Referring now in detail to the drawings, the numeral 1 represents the handle and 2 the body of my device, the former being 35 composed of two flat members 1^a and 1^b, and the latter of two similar members 2^a and 2^b. A channel 3 extends through part of said handle and communicates with a relatively wider channel 4 in the body 2. A slot 6 is provided in the handle 2 communicating with the channel 3, and a pin 40 or button 5 extends through said slot and rests slidably therein. A member 7 is slidably mounted in the channel 3 and extends into the channel 4, said member being 45 loosely attached to the button 5. A bend or hump 8 is provided near the end of the member 7, and a spring 9, attached to the bottom of the channel 3, presses upon said member 7 adjacent the hump 8.

Pivottally mounted at 11 in the channel 4 is an eccentric disk 10 having the member 7 pivottally attached near the periphery thereof. An arcuate slot is cut parallel to 50 the periphery of said disk, and therein lies a pin 14 in slidable relation. Said pin 14

is rigid with a comb 15 slidably mounted between guides 16 in the body 2. Brushes 17 are attached in the usual manner to the portion 2^a of the body 2.

The operation of the device is now obvious. In order to extend the comb 15, the button 5 is pressed forward (toward the brush portion), whence the rotating disk 10 forces the pin 14, and consequently the comb 15, outward from the body 2. In order to conceal the comb, the button is pressed in the reverse direction.

The engagement between the spring 9 and the hump 8 of the member 7 causes the 70 comb 15 to be releasably retained in either of its extreme positions.

I claim:

1. A device of the class described comprising a frame, a channel in said frame, a comb slidably mounted in said frame, a disk eccentrically and pivotally mounted in said channel, a pin on said comb, an arcuate slot near the periphery of said disk, said pin having slidable engagement in said slot, a slot in said frame having communication with said channel, a button slidable in said second-named slot, a member having one end slidably mounted in said channel and the other end pivotally attached to said disk near the periphery thereof, said button having loose connection with said member, and spring means releasably retaining said comb in either of its extreme positions.

2. A device of the class described comprising a frame, a channel in said frame, a comb slidably mounted in said frame, a disk eccentrically and pivotally mounted in said channel, a pin on said comb, an arcuate slot near the periphery of said disk, said pin having slidable engagement in said slot, a slot in said frame having communication with said channel, a button slidable in said second-named slot, a member having one end slidably mounted in said channel and the other pivotally attached to said disk near the periphery thereof, said button having loose connection with said member, a spring having one end attached to said frame within said channel, a hump in the slidable end 105 of said member, said spring adapted to press upon said slidable end and to retain said member releasably in either extreme position.

In testimony whereof I affix my signature. 110

FRANCISZEK KUCAB.
